UNITED STATES PATENT OFFICE.

EDWARD J. FRITTON, OF LOCKPORT, NEW YORK.

PRESSURE-CONTROLLING DEVICE.

Application filed February 4, 1927. Serial No. 165,987.

This invention relates to the automatic control and regulation of pressure in pressure chambers, boilers, manifolds and the like, and it is an object of the invention to provide a device of this character which is fully automatic, positive and unfailing in action and thoroughly safe in all of the many uses to which it is adapted.

A further object of the invention is to provide a controlling device which is automatically responsive to the pressure or equivalent factor in the chamber or the like to be controlled and which in turn automatically acts to control or regulate the pressure creating or transmitting medium.

A further object relates to the provision of micrometric adjusting means in connection with an automatic pressure controller whereby any desired predetermined pressure may be maintained in the chamber or the like with which such controller is associated.

A more specific object of the invention relates to the provision of such a pressure controlling device in combination with a double acting or other type of pump whereby the pressure in the receiving or pressure chamber which is supplied by the pump as well as in the cylinder or cylinders of the pump, is automatically and minutely governed.

The fulfillment of these objects as well as others of both major and minor importance which will appear hereinafter, is accomplished by the structure chosen for the purposes of illustration in the accompanying drawings, wherein the single figure is a view partly in elevation and partly in section of a pump unit with my novel pressure controlling device combined therewith.

The pressure controlling device which forms the subject of my invention is herein shown as embodied in a pressure producing pump of the two cylinder type. The pump comprises a pair of opposed and horizontally aligned cylinders, within which a pair of connected pistons 2 operate. The pistons are reciprocated jointly by means of yoke 3 and crank pin 4 connected with any suitable actuating mechanism. The cylinders 1 are in communication with an intake manifold 5 through the medium of intake check valves 7. On the outlet side of the cylinders there is provided a pressure chamber 6 which also has communication with the two opposed cylinders through exhaust check valves 8.

My invention may be applied to a pump substantially as described above or to prac-

tically any other type of either single or double acting pump. As shown in the drawings, however, my invention is applied to the above described pump and to this end I provide a by-pass manifold 9 which connects and places in communication the outlet ports of the two opposed cylinders. This by-pass manifold is disposed intermediate the cylinders and the respective exhaust check valves. At some intermediate points in the by-pass manifold I provide a valve mechanism for variably controlling the passage of fluid through the manifold from one cylinder to the other. This valve mechanism may take a number of different forms but as herein shown it comprises a cylindrical sleeve 11 within which is adapted to reciprocate a plunger type of valve 10. The sleeve 11 is provided with a number of ports 12 which afford communication with the opposite portions of the manifold. The plunger 10 is normally spring pressed by means of a spring 13 to maintain the plunger in position where-in the ports 12 are closed. For the accurate adjustment of this spring I have provided a finely threaded member 14 having engagement with corresponding threads in a spring housing cup 14', which member supports and serves to adjust the end convolution of the spring. A lock nut 15 is provided for locking the device securely in any adjusted position. The plunger 10 is connected to a valve stem 17 which in turn is operatively connected in such a manner as to be actuated by the pressure within the pressure manifold 6. For the purpose of rendering the valve 10 responsive to the pressure in the manifold 6 I have provided a form of fluid motor for acting directly on the valve stem in proportion to the degree of pressure in the pressure manifold.

By way of illustration I have shown this fluid motor to take the form of a housing 16 having a diaphragm 19 and a cap 19'. The valve stem is provided with a head 18 which rests on the under-surface of the diaphragm while the cap above the diaphragm is provided with a small chamber into which the pressure of the pressure manifold is introduced through the connecting pipe 20. It is apparent that the valve stem 17 projects centrally through the housing 16 and that a suitable stuffing box is provided to prevent undesired leakage.

The operation of the device should be apparent from the foregoing description. Considering first the by-pass manifold 9 and the reciprocating plunger valve 10, it is apparent

that if the valve stem is in a position to close the ports 12, the pump will be effective to introduce fluid under pressure into the pressure chamber 6 and the by-pass manifold 9 will perform no substantial function. If, however, the valve 10 is moved to a position which permits a partial or unrestricted communication between the two sections of the by-pass manifold, it is obvious that the fluid 10 expelled from one cylinder will be transferred through the by-pass manifold, through ports 12 and into the opposed cylinder. By so providing for the by-passing of the fluid expelled from one cylinder to the 15 other it is also apparent that the pressure on the pump side of the exhaust check valves is reduced to some point below the pressure which is maintained in the pressure manifold. It should also be clear that the discharging 20 of fluid from one cylinder into the other serves to impose a pressure upon the pump side of the intake check valve of such other cylinder, thereby precluding the possibility of that check valve being opened and taking on a 25 new supply of fluid. By connecting the reciprocating valve 10 with the fluid motor which is responsive to the pressure in the pressure manifold, it is apparent that the time and amount of by-passing of the fluid 30 discharge from the pump cylinders will be governed by the pressure in the receiving manifold. The pressure at which the fluid motor is effective to cause the opening of the ports 12 may be minutely governed by suitable 35 adjustment of the threaded bolt 14.

By employing a pressure controlling device such as described above it is possible to maintain the pressure in a receiving chamber at any desired value and at the same time 40 relieving the pressure on the pump cylinders or other pressure creating means. It is apparent that the operation of my device involves no loss of time or material, it simply 45 acting to render the work of the pumps ineffective in a greater or less degree. This is a distinct advance over other forms of devices for this general purpose, in many of which the controlling device operates to cut off or reduce a motive power by which the pressure is 50 created. With my invention it is not necessary to discontinue the operation of the pumps at any time by reason of the pressure within the pressure chamber reaching too high a value, nor is it necessary to give any attention 55 whatever to a pump provided with my controlling device, since its entire operation is both safe and automatic.

Attention is again directed to the fact that my pressure controlling device operates 60 both to impose a pressure on the pump side of the intake valves and to reduce the pressure on the pump side of the exhaust check valves. The pressure within the receiving manifold will thus maintain the exhaust 65 check valves in closed position by reason of

the fact that such pressure is greater than the reduced pressure on the pump side of such valves. In the case of the intake check valves the pressure imposed thereon by the discharge 70 of one pump cylinder into another is substantially greater than the normal pressure in the inlet manifold, thus causing the valves to remain closed.

The specific pump structure herein shown and described forms no part of the present invention except in so far as its combined relation to my improved pressure controlling device is concerned.

My invention is by no means restricted in its application to a pump of the type herein shown, nor to any other single type of pump, but is applicable to all types of pumps as well as to other forms of pressure creating and transmitting means employed in connection with pressure storage means. For example, 85 the invention might be as readily applied to a single cylinder, double acting pump as to the pump herein shown, in which case the pressure controller would operate to permit the surge of fluid from one end of the cylinder to the other and on opposite sides of the piston. In a manner similar to that herein shown, the invention might be applied to a pump comprising any desired number of cylinders.

What I claim is:

1. In a device of the character described, the combination with a two cylinder pump of the horizontally aligned and opposed type, of a by-pass manifold connecting the discharge ports of the two cylinders, discharge 100 check valves in communication with the respective cylinders and manifold and a pressure chamber in communication with said discharge check valves, of a valve disposed in said by-pass manifold for controlling the 105 passage therethrough of fluid discharged from one cylinder into the other and means responsive to the pressure in said pressure manifold for actuating the said valve.

2. In a device of the character described, 110 the combination with a pump comprising horizontally aligned and opposed cylinders having check valve controlled communication with a pressure receiving chamber, of a by-pass manifold interposed between the cylinders and the check valves and placing the said cylinders in communication, a valve disposed within said by-pass manifold, a fluid motor mounted on said by-pass manifold and having communication with said pressure manifold and an operative connection between said fluid motor and said valve.

3. In a pump of the horizontally opposed cylinder type embodying a discharge port for each cylinder, the combination therewith of a removable manifold unit having a longitudinal passage and transverse passages adjacent the ends thereof communicating with said longitudinal passage, said transverse passages being adapted to register with said

- discharge ports at one side of said manifold, a removable check valve associated with each said transverse passage at the opposite side of said manifold, a pressure manifold having 5 ports registering with said check valves, means for holding said first mentioned manifold, said check valves and said pressure manifold in operative engagement with each other and with said pump, a valve disposed 10 in the longitudinal passage of said first mentioned manifold for controlling the by-passing of fluid therethrough, and means responsive to the pressure in said pressure manifold for governing the action of said valve.
- 15 4. In a double acting pump, the combination with the discharge ports thereof, of a by-pass manifold unit, a pair of check valve units and a pressure manifold unit, each unit being detachable and structurally independent 20 of the others, means for holding said two manifolds together with said check valve units interposed therebetween and said by-pass manifold in communication with said discharge ports, and means for controlling 25 the passage of fluid through said by-pass manifold.
5. In a double acting pump, the combina-
- tion with the discharge ports thereof, of a by-pass manifold unit supported on said pump and having communication with said 30 discharge ports, of a pair of check valve units disposed on said manifold adjacent the ends thereof and having communication therewith, of a pressure chamber unit disposed on said check valve units and communicating 35 with the latter, means for clamping said several units together and to said pump, and means for controlling the passage of fluid through said by-pass manifold.
6. In a device of the character described, 40 the combination with a plurality of pressure creating devices and a pressure receiving device in communication therewith, of a by-pass manifold communicating with said pressure creating devices, of a valve disposed in said 45 manifold for regulating the flow of fluid therethrough, a spring for urging said valve toward closed position, a stem secured to said valve and extending outside said manifold, and a fluid motor operatively associated with 50 said valve stem and with said pressure receiving device.

In testimony whereof I affix my signature.
EDWARD J. FRITTON.
